UNITED STATES PATENT OFFICE.

CLARICE PFEFFER, OF SAN JOSE, CALIFORNIA.

DESIGN FOR A CHILD'S SUIT.

56,988.

Specification for Design.

Patented Jan. 25, 1921.

Application filed July 8, 1920. Serial No. 394,834. Term of patent 14 years.

To all whom it may concern:

Be it known that I, CLARICE PFEFFER, a citizen of the United States, and resident of San Jose, county of Santa Clara, State of California, have invented a certain new, original, and ornamental Design for Children's Suits, of which the following is a specification.

Reference is to be had to the accompanying drawing in which Figures 1 and 2 are opposite face views of a garment embodying my design.

The essence of the invention resides in the distinctive, ornamental and general appearance imparted thereby to the child's suit, it being understood that my claim includes all substantial equivalents of the design as shown.

I claim:

The ornamental design for a child's suit, as shown.

In testimony whereof I have hereunto set my hand.

CLARICE PFEFFER.
